UNITED STATES PATENT OFFICE.

LLEWELLYN A. HURLBURT, OF FAIRBURY, NEBRASKA.

SICKLE.

931,764.

Specification of Letters Patent. Patented Aug. 24, 1909.

Application filed May 11, 1908. Serial No. 432,068.

To all whom it may concern:

Be it known that I, LLEWELLYN A. HURLBURT, a citizen of the United States, residing at Fairbury, in the county of Jefferson and 5 State of Nebraska, have invented certain new and useful Improvements in Sickles, of which the following is a specification.

This invention relates to improvements in sickles and has among its salient objects to 10 provide a device which can be used to trim lawns, shrubbery, etc., without necessitating bending or stooping on the part of the operator; to provide a device the blade of which is rigidly supported at each end and is provided 15 with a double cutting edge so as to operate when swung in both a backwardly and forwardly direction; to provide an extremely simple and durable construction in which all parts lie substantially in the same 20 plane or planes; and in general to provide an improved construction of the character referred to.

The invention will be understood from the following description, reference being had 25 to the accompanying drawings in which—

Figure 1 is a side elevation of the device and Fig. 2 is a cross sectional view taken on lines 2—2 of Fig. 1.

Referring to the drawings 1 designates as 30 a whole a loop-like frame member which in the present embodiment of the invention is made generally rectangular as to its main body portion and comprises side frame members 2 and a lower cross piece 3 preferably made integral. At the upper end of the rectangular portion of the frame the side members 2 are first bent inwardly as shown at 4 and then outwardly to form parallel extensions 5, these latter serving as shanks for 35 the reception of the handle 6. This handle is detachably secured to the frame member by means of suitable through-bolts 7. In order to increase the rigidity of the frame member, a brace rod 8 is rigidly united to 40 the frame at the points where the sides of the latter are bent inwardly. Each end of the brace rod is screw-threaded and extends through suitable apertures in the side members 2 to which it is detachably secured by 45 suitable nuts 9.

As seen more clearly in Fig. 2 the lower cross piece 3 is preferably made of relatively wide strap iron the upper face of which is flat and to its upper face is suitably secured, as by rivets 11, a double edged cutting blade 55 10. The width of this blade is greater than the width of the cross piece 3 so that the edges of the blade extend beyond either side of the frame, in order to afford effective cutting edges. The arrangement is such that 60 the bar which carries the blade largely protects the latter against contact with the sidewalks, curbs, etc., while the wide frames protect the user against accidentally cutting himself. Incidentally it will be noted that 65 all of the parts are in the same general plane with each other, thus making a very compact device which can be readily shipped or stored in comparatively small space. Inasmuch as the handle extends at right angles to the 70 blade the device can of course be operated without necessitating bending or stooping.

The device is extremely strong and durable for the reason that the blade is protected and supported throughout its full 75 length and at the ends.

While I have herein shown what I deem to be a preferred embodiment of the invention, at the same time it is apparent that the device can be varied in details of construction without in any manner departing from the spirit of the invention.

I claim as my invention:

1. In a sickle, the combination with a handle, of a frame comprising a pair of side 85 members substantially parallel at their lower ends and converging inwardly at their upper ends, parallel shank extensions at the upper extremities of said converging portions of the side members, an integral cross-piece 90 connecting the lower ends of the side members, a brace-rod connecting the side members at points remote from the cross-piece, and a double edged blade secured to the inner face of said cross-piece and extending 95 beyond the sides of the latter.

2. In a sickle, the combination with a frame comprising a pair of side members provided at their upper ends with a shank extension to receive the handle, of a handle 100

seated in said shank extension and substantially in alinement with the frame, an in-turned blade support upon the lower end of said frame, and a double edged blade 5 cured to the upper edge of said in-turned blade support, and extending beyond the sides of the latter, whereby the edges of said

blade are protected from contact with the ground.

LLEWELLYN A. HURLBURT.
